[57] CLAIM

The ornamental design for a protective tip cover for skis, as shown and described.

DESCRIPTION

FIG. 1 is a top plan view of a protective tip cover for skis showing my new design;

FIG. 2 is a bottom plan view thereof;

FIG. 3 is a side elevation view thereof;

FIG. 4 is a front elevational view thereof;

FIG. 5 is a rear view thereof;

FIG. 6 is an oblique view of the bottom thereof; and,

FIG. 7 is an oblique view of a ski tip with the protective tip cover of my design in place thereon.

FIG. 1

FIG. 3

FIG. 2

FIG. 4

FIG. 5

FIG. 6

FIG. 7
